UNITED STATES PATENT OFFICE.

AMELIE TANRON, OF SAN RAFAEL, CALIFORNIA.

FLATIRON SUPPORT.

Application filed October 13, 1925. Serial No. 62,221.

This invention relates to a support for flatirons and the like and has for its object the provision of a simple device of this character which may be cheaply manufactured and readily positioned for use on an ironing board.

Another object of my invention is to provide a flatiron support having a table or raised surface for supporting the flatiron, 10 provided with a peripheral upstanding edge to avoid the slipping of the iron from the support and which edge assists in the ready positioning of the flatiron thereon.

A further object of the invention is to 15 provide a support of the character specified having an inclined surface leading from the surface of the ironing board to the elevated surface on which the flatiron is supported whereby the flatiron can be slid directly to and from the surface of the 20 ironing board to the support without the necessity of lifting the iron, and thus avoiding unnecessary manual labor on the part of the user of the flatiron.

25 A still further object of the invention is to provide a flatiron support having the desirable features pointed out which may be formed as an integral unit from a flat sheet of suitable metal, thereby simplifying its 30 construction and reducing the cost of manufacture to a minimum, and producing a unit of rugged construction without parts that are likely to get loose or out of order.

The invention possesses other advantageous features, some of which with the foregoing will be set forth at length in the following description, where I shall outline in full that form of the invention which I have selected for illustration in the drawings accompanying and forming part of the present specification. In said drawings I have shown several forms of devices embodying my invention, but it is to be understood that I do not limit myself to such forms, since 40 the invention as set forth in the claim may be embodied in a plurality of other forms.

Referring to the drawings:

Figure 1 is a plan view of a flatiron support embodying my invention, illustrating 50 one mode of securing the same to an ironing board.

Figure 2 is a section taken on the line 2-2 of Fig. 1.

Figure 3 is a section taken on the line 55 3-3 of Fig. 1, and

Figure 4 is a right end view of Fig. 1

illustrating a modified type of means for securing the support to the ironing board.

In the drawings, I have shown a flatiron support 1, which is made of a suitable metal, such as zinc for example, and formed with a table or elevated supporting surface 2 for the flatiron. The surface 2 is preferably rectangular in shape as best shown in Fig. 1, and provided on two of its parallel sides with an upstanding edge 3 and 4. Preferably the entire unit is formed from a single piece of sheet metal in which case the piece of metal forming the surface 2 is bent up at right angles to form the edges 3 and 4. In order to strengthen said edges as well as to form a holder for a sheet of asbestos 5, or other suitable heat insulating material, positioned on the lower side of the surface 2, the edges 3 and 4 are each doubled and bent 70 downwardly, extending a slight distance below the surface 2 at which point they are bent inwardly to form L-shaped supports 6 and 7 respectively for the longitudinal edges of the asbestos 5, as best shown in Fig. 3. The surface 2 is also preferably formed with several ridges 8 parallel with the edges 3 and 4 on which the flatiron may rest, and thereby prevent dangerous heating by the flatiron when on the support. One 75 end of the surface 2, which I shall refer to as the rear end of the same is formed with an edge 9 at right angles with and formed similarly to the edges 3 and 4 just described; however the edge 9 is provided 80 with a longer downward extension or flap 10 which provides a support for the unit as well as means for securing the same to the ironing board 11. The flap or extension 10 is cut inwardly at a number of points a 85 suitable distance from its outer edge so as to provide a series of independent flaps. In the present instance four of such cuts are provided as indicated in dotted lines at 12 to 15 inclusive in Fig. 1, thus forming five 90 separate flaps 16 to 19 inclusively. Flaps 16, 18 and 20 are bent inwardly underneath the surface 2 at right angles with the edge 9, while the alternate flaps 17 and 19 extend downward vertically. The flaps 16, 18 and 20 form rests on the ironing board 11 for the unit, as shown best in Fig. 2, the same being designed to support the unit a suitable distance above the ironing board 110 surface. The vertical flaps 17 and 19 are respectively provided with apertures 21 and 22 to receive screws 23. The unit thus

described is positioned on the ironing board 11 with the flaps 16, 18 and 20 resting on the surface thereof and with flaps 17 and 19 against the edge thereof and secured to 5 said edge by screws 23. The end opposite the rear end having edge 9, which I shall refer to as the forward end of the unit is provided with an inclined surface 24, which extends forwardly from the surface 2 10 proper and beyond the edges 3 and 4, down to the surface of the ironing board at an angle so that a flatiron may readily be slid from the ironing board surface onto the surface 2 of the unit described. Preferably, 15 the asbestos element 5 extends underneath the inclined surface 24 and is secured thereto by bending the edge of said surface inwardly as indicated at 25. The part 24 is also provided if desired with an aperture 26 20 adapted to receive a screw 27 by means of which the unit is secured to the ironing board at its forward end. If desired, the forward ends of the edges 3 and 4 may be bent outwardly slightly as indicated at 28 25 and 29.

In the modification shown in Fig. 4, I

have shown a different manner of attaching the rear end of the unit to the ironing board. In this case, the flaps 17 and 19 are not screwed to the ironing board but are 30 held against the same by a strap 30 in a manner readily understood.

I claim:

A flatiron support comprising an integral unit formed from a sheet of metal comprising 35 a horizontal wall for supporting the flat iron, one end of which is bent upwardly and then bent downwardly to provide a support for the unit, and the opposite end of which is bent downwardly so as to provide an inclined surface extending from the surface of the ironing board to said horizontal wall, said first-mentioned downwardly bent portion being provided with a plurality of flaps, some of which are bent inwardly at 40 45 right angles to form a rest on the upper surface of the ironing board and others of which are adapted to engage the edge of the ironing board.

In testimony whereof, I have hereunto 50 set my hand.

AMELIE TANRON.
